UNITED STATES PATENT OFFICE

JAMES A. HARPS, OF GREENFIELD, OHIO

CONTAINER OR THE LIKE

Application filed June 28, 1930. Serial No. 464,637.

This invention relates to improvements in a container for light fluids such as gasoline, light oils, or the like.

An object of the invention is to provide a container for fluids of the above character, constructed so as to preclude splashing out of the fluid when the container is carried.

Another object is to provide a container of the above character which has a novel spout structure that prevents the fluid of the container from suddenly gushing out when poured from the container, thereby facilitating directing the fluid as it is poured.

Another object is to provide a container head having a novel baffle structure and spout which may be inexpensively manufactured.

These and other objects are attained by the means described herein and disclosed in the accompanying drawings, in which:

Fig. 1 is a top plan view of a container embodying the invention.

Fig. 2 is a cross-sectional view taken on line 2—2 of Fig. 1.

Fig. 3 is an enlarged top plan view of a portion of the container head showing the baffle, the spout being removed.

Fig. 4 is a cross-sectional view taken on line 4—4 of Fig. 3.

The purpose of this invention is to provide a container for fluids such as gasoline, kerosene or the like, which is provided with a spout having means cooperating therewith to preclude splashing of the fluid from the container during transportation thereof. The spout structure disclosed herein also precludes sudden gushing of the fluid from the container when the liquid is poured, thereby rendering it easy to direct the fluid delivered from the spout. In the drawings, 5 represents a container of any desired shape, that disclosed being cylindrical in form. The container is provided with a bottom 6 and a head 7, both of which are preferably permanently secured to the body of the container. The head 7 is provided with a fluid discharge opening 8, which is formed by punching out a portion of the head to the extent that the punched out portion provides a baffle plate 9 lying in a plane parallel to and below the plane of the head. The portions 10 remain

after the punching operation, forming radially disposed baffle supports integral with the baffle and head. The supports preferably extend downwardly within the container 5. The cuts 11 defining each baffle support permit the baffle plate to be disposed sufficiently below the plane of the container head to render the discharge opening capable of delivering fluid at the same rate as the opening 12 of spout member 13. It should be readily apparent that a baffle plate formed in accordance with the above teaching, is very durable and may readily be adjusted in the punching operation to deliver a predetermined quantity of fluid.

Surrounding the fluid discharge opening is an annular depression 14 which provides a seat for the lower end 15 of the spout member. As indicated at 16, Fig. 2, the spout member has its lower edge placed within the annular depression, after which solder or other securing means is applied for holding the spout member in position. It is to be noted that the baffle plate is of substantially the same diameter as the opening from which it is punched, and that it is substantially in axial alignment with said opening.

The head of the container may be provided with a filler neck 17 which may be used in filling the container. The filler neck is provided with any suitable type of cap or plug 18. Upright perforate lugs 19 on the container head provide a means whereby the handle 20 may be attached to facilitate carrying of the device.

When a device constructed in accordance with the invention is emptied of fluid through the spout member 13, the disturbance ordinarily caused by entry of air during discharge of the liquid is scarcely noticeable. The baffle plate prevents the head of fluid within the container from discharging the fluid in a forceful stream. When the container is filled with a liquid and is transported, or carried by means of a handle 20, there can be no splashing of fluid from the spout, because of the interception of the fluid by the baffle plate. It is to be understood that the shape of the container and of the spout and discharge opening are not of importance.

in the present invention, and that various modifications and changes in structural details of the device may be made, within the scope of the claims without departing from the spirit of the invention.

5 What is claimed is:

1. In a device of the class described the combination with a container, of a head for the container having a filling opening and a fluid discharge opening therein, a baffle plate on the head substantially parallel thereto and disposed in spaced relations with the plane of the head and adjacent to the fluid discharge opening to preclude splashing out of the fluid contents of the container when the container is transported, a closure member for the filling opening, and a spout on the head encircling the fluid discharge opening.

10 2. In a device of the class described the combination with a container, of a head for the container, an integral baffle plate struck from the head to provide a fluid opening above the baffle plate, a series of integral radially disposed baffle supports connecting the head and baffle plate, and a spout member 15 encircling the opening and having a discharge port of substantially the same discharge capacity as the fluid opening.

3. In a device of the class described the combination with a container, of a head for the container, an integral baffle plate struck from the head to provide a fluid opening directly above the baffle plate, and a series of integral radially disposed baffle supports 20 connecting the head and baffle plate.

4. In a device of the class described the combination with a container, of a head for the container, and an integral baffle plate struck from the head to provide a fluid opening, said baffle plate being of substantially the same size and area as the opening and disposed in axial alignment with said opening.

45 5. A head for a fluid container comprising an integral baffle plate struck from the material of the head to provide a fluid discharge opening, baffle supports integral with the baffle plate and head for supporting the baffle plate in a position adjacent the fluid discharge opening, and an annularly depressed seat formed on the head and encircling the fluid discharge opening for reception of a spout member.

6. A head for a fluid container comprising 50 an integral baffle plate struck from the material of the head to provide a fluid discharge opening, baffle supports integral with the baffle plate and head for supporting the baffle plate in a position adjacent the fluid discharge opening, and a seat for a spout member encircling the said opening.

7. A head for a fluid container comprising 55 an integral baffle plate struck from the material of the head to provide a fluid discharge opening and baffle supports integral with the

baffle plate and head for supporting the baffle plate in a position adjacent the fluid discharge opening.

In testimony whereof, I have hereunto subscribed my name this 27th day of June, 1930. 70

JAMES A. HARPS.
